H. W. SCOTT.
COMBINATION ROOF FRAMING TOOL.
APPLICATION FILED DEC. 23, 1918.

1,342,232.

Patented June 1, 1920.

UNITED STATES PATENT OFFICE.

HERMAN W. SCOTT, OF GARDINER, MAINE.

COMBINATION ROOF-FRAMING TOOL.

1,342,232.

Specification of Letters Patent. Patented June 1, 1920.

Application filed December 23, 1918. Serial No. 268,061.

To all whom it may concern:

Be it known that I, HERMAN W. SCOTT, a citizen of the United States, residing at Gardiner, in the county of Kennebec and 5 State of Maine, have invented certain new and useful Improvements in Combination Roof-Framing Tools, of which the following is a specification.

This invention relates to an improved 10 square for use in cutting and assembling of beams to obtain the proper angle when building the roof of a building and the device may be termed a combination roof framing tool. While it is used principally 15 when constructing a roof it is to be understood that its use is not limited to this particular use but may be used wherever it may be employed with advantage. The principal object of the invention is to provide 20 a square so constructed that the blade may be moved to a desired angle and secured in this position and at the same time a second blade pivotally connected with the stock or handle angularly adjusted thereby 25 permitting the angle of the second blade to be ascertained through the medium of a scale or protractor connected with the main blade of the square. Another object 30 of the invention is to provide improved means for releasably connecting the protractor with the square blade, the fastening means being so constructed that the protractor will be held in tight engagement with the blade but permitted to be easily 35 and quickly released when desired. Another object of the invention is to provide an improved type of actuating device for the auxiliary blade pivotally connected with the handle, this actuating device being slidably 40 connected with the shank or handle and actuated by the blade of the square when the blade is swung upon its pivot. This invention shows certain accompanying drawings wherein—

45 Figure 1 is a plan view of the improved square,

Fig. 2 is a view showing the improved square in elevation,

Fig. 3 is an enlarged transverse sectional view through the handle portion of the square on the line 3—3 of Fig. 2,

Fig. 4 is a sectional view taken along the lines 4—4 of Fig. 1,

55 Fig. 5 is a sectional view taken along the lines 5—5 of Fig. 1,

Fig. 6 is a fragmentary view of the han-

dle portion of this square looking from the opposite side to that shown in Fig. 1. This square is provided with a handle or stock formed of two plates or side sections 10 and 11 which are formed of angle iron to provide the side flanges 12 and end flanges 13. These side plates are held in spaced relation by the spacing strips 14 and 15 thus providing a slot or pocket 16 in the handle. 60 Openings 17 are formed in one of the side plates to receive spirit level 18 so that this device may be used as a level as well as being used as a square. This handle is further provided in the side plate 10 with a 65 longitudinally extending slot 19 having an enlarged end portion 20 and is provided in the side plates 11 with a cut out 21 forming pointers 22 and further providing a sight opening so that the quadrant to be herein- 70 after described may be seen through the handle. 75

The blade 23 is positioned between the side plates or bars of the handle and pivotally mounted through the medium of the 80 pivot pin 24 and is provided with an auxiliary arm 23' at right angles to the blade and which lies longitudinally between the side plates when the blade is extending in its normal position at right angles to the handle. This blade and arm carry protractor 85 25 which extends from the auxiliary arm to the blade. This protractor will be pivotally connected with the auxiliary arm as at 25^a so that it may be swung out of the 90 normal position disclosed in Fig. 1 when desired and has its free end portion 26 reduced to fit into a cut out or seat 27 formed in the blade 23. A pin 28 is carried by the reduced end portion of the protractor and fits into an opening 29 formed 95 in the blade 23 and in order to retain this pin against accidental removal from the opening 29 there has been provided a latch or fastener 30 which is slidably mounted 100 in a seat 31 formed in the protractor. When this latch is moved to the position shown in Figs. 1 and 4 it will be readily seen that the protractor will be securely connected with the blade 23. From an inspection of 105 Fig. 5 it will be readily seen that this latch cannot slip out of engagement with the protractor and become lost as the socket 31 is undercut and the latch is provided with side ribs fitting into the undercut side portions of the seat. A set screw 32 is carried by the side bar 11 of the handle and will 110

engage the protractor to secure the same against movement thus releasably holding the blade in an adjusted position. It will thus be seen that with this construction the 5 blade 23 can be swung to the desired angular relation with respect to the stock or handle secured in this position by the set screw 32 the angle of the blade being ascertained through the medium of the point- 10 ers 22.

An auxiliary blade 33 having a longitudinally extending flange 34 and a longitudinally extending slot 35 is positioned longitudinally of the plate 10 of the stock 15 or handle and is pivotally mounted upon one terminal of a pivot pin 36 mounted in bearings 37 and provided with a turning nut 38 so that this pivot pin may be rotated and thus moved out of engagement with the 20 blade 33 to release the latter. The pin 36 is threaded in one of the bearings 37 so that longitudinal adjustment thereof is effected during rotation. It will thus be seen that when desired this blade 33 can be disconnected from the stock. It is desired to 25 have this auxiliary blade moved through the medium of the blade 23 and there has therefore been provided a slide slidably connected with the plate 10 of the stock and having 30 engagement with the blade 33 and further having a tongue 41 for engagement by the blade 23.

This slide is formed of sheet metal stamped and bent to provide the base 39 35 from which extends the standard 40 and finger 41. The base is bent to provide a longitudinally extending rib 42 engaged by the securing plate 43 secured to the side plate 10 and from an inspection of Figs. 1 and 3 40 it will be readily seen that this plate 43 will hold the slide in engagement with the stock but permit sliding movement of said slide longitudinally of the stock. The standard 40 carries a pin 44 which passes through the 45 slot 35 of the auxiliary blade so that when the slide is moved longitudinally of the stock this pin will cause the auxiliary blade to swing upon its pivot pin. The tongue 41 extends from the base plate 39 of this slide 50 through the slot 19 and as shown in Fig. 3 extends through the space between the plates 10 and 11 into operative position with respect to the blade 23. When this blade 23 is swung upon its pivot 24 it will engage the 55 tongue 41 and will therefore move this slide longitudinally of the stock and thereby adjust the angle of the auxiliary blade. When it is desired to return the auxiliary blade to the original position it is simply necessary 60 to swing it to this position or move the slide and thus cause the blade to swing upon its pivot pin to the original position. It will thus be seen that this auxiliary blade may be easily swung to an adjusted position and 65 retained in the adjusted position by fric-

tional engagement between the base plate and clamping plate and further that the angle of the auxiliary blade can be easily ascertained through the medium of the protractor of the main blade.

70

What I claim is:

1. A square comprising a handle having a longitudinally extending slot, a blade pivotally mounted in the slot of the handle and having an arm normally extending through 75 the slot, a protractor having one end portion pivotally connected with the arm of the blade, means releasably connecting the opposite end portion of the protractor with the blade, and means for engaging the protractor to releasably hold the same against movement and retain the blade in an adjusted position.

2. A square having a handle comprising side plates positioned in spaced relation, a blade pivotally mounted between the side plates of the handle and having an arm normally extending between the side plates, a protractor having one end portion connected with the arm and the opposite end portion thereof releasably connected with the blade, and means carried by one of the side plates of the handle to engage the protractor and releasably hold the blade against movement.

3. A square comprising a handle, a blade pivotally connected with the handle and including an angularly directed arm, a protractor having one end portion connected with the side arm and having its opposite 100 end portion extending in overlapping relation to the blade, a pin carried by the protractor and extending through an opening formed in the blade, a latch slidably connected with the protractor for movement 105 into and out of engagement with the blade and means carried by the handle for engaging the protractor to releasably hold the same against movement and retain the blade in an adjusted position.

4. A square comprising a handle, a blade pivotally connected with the handle, a protractor having one end portion extending in overlapping relation to the blade, a pin carried by the overlapping end portion of the 110 protractor and extending through an opening formed in the blade, a latch movably connected with the protractor for movement into and out of engagement with the blade, and means carried by the handle to engage 115 the protractor and releasably hold the same against movement with relation to the handle.

5. A square comprising a handle, a blade pivotally connected with the handle, means 125 for indicating the angle at which the blade extends with respect to the handle, an auxiliary blade pivotally connected with the handle, and means for adjusting angle of the auxiliary blade slidably connected with the 130

- handle and having a part extending into the path of movement of the first mentioned blade.
6. A square comprising a handle, a main blade pivotally connected with the handle, means for indicating the angle of the main blade with respect to the handle, an auxiliary blade pivotally connected with the handle, and actuating means for the auxiliary blade slidably connected with the handle and having a part extending into the path of travel of the main blade for receiving movement therefrom when the main blade is swung in one direction.
- 15 7. A square comprising a handle, a main blade pivotally connected with the handle, an auxiliary blade pivotally connected with the handle for movement in a plane at right angles to the plane of movement of the main blade, and actuating means for the auxiliary blade carried by the handle and receiving movement from the main blade when the main blade is swung in one direction.
- 20 8. A square comprising a handle, a main blade pivotally connected with the handle, an auxiliary blade pivotally connected with the handle, a slide having a base slidably connected with the handle, a standard extending from the base and having sliding engagement with the auxiliary blade thereby causing pivotal movement to the same when the slide moves upon the handle, and an abutment extending from the base into

the path of movement of the main blade and engaged by the main blade to impart movement to the slide when the main blade is swung in one direction.

35 9. A square comprising a handle, a main blade pivotally connected with the handle, the handle having a longitudinally extending slot, a slide slidably connected with the handle and having a standard in sliding engagement with the auxiliary blade and a tongue extending into the slot of the handle into the path of movement of the main blade 40 whereby the slide will be moved to impart swinging movement to the auxiliary blade 45 when the main blade is swung in one direction.

10. A square comprising a handle having 50 side plates, one of the side plates being provided with a longitudinally extending slot, a main blade pivotally mounted between the side plates of the handle, an auxiliary blade pivotally connected with the slotted side 55 plates for movement in a plane at right angles to the plane of movement of the main blade, a slide slidably connected with the handle and having sliding engagement with the auxiliary blade, and a tongue extending 60 from the slide into the path of movement of the main blade.

In testimony whereof I affix my signature hereto.

HERMAN W. SCOTT.
